[57] CLAIM

The ornamental design for a combined cup and plate holder, as shown and described.

DESCRIPTION

FIG. 1 is a perspective view of a combined cup and plate holder showing my new design;
FIG. 2 is a top plan view thereof; and,
FIG. 3 is a cross-sectional view taken along line 3—3 of FIG. 2, the cup and plate shown in broken lines for illustrative purposes only.
The undisclosed bottom view is unornamented.
